(57) **CLAIM**

The ornamental design for a stand for monitor, as shown and described.

DESCRIPTION

1. Stand for monitor
- 1.1 : Perspective
- 1.2 : Rear perspective view
- 1.3 : Front
- 1.4 : Back
- 1.5 : Left
- 1.6 : Right
- 1.7 : Top
- 1.8 : Bottom
- 1.9 : Rear perspective view showing a state of use with a monitor
- 1.10 : Perspective
- 1.11 : Rear perspective view
- 1.12 : Front
- 1.13 : Back
- 1.14 : Left
- 1.15 : Right
- 1.16 : Top
- 1.17 : Bottom

(Continued)

1.18 : Rear perspective view showing another state of use with a monitor
1.19 : Perspective
1.20 : Rear perspective view
1.21 : Front
1.22 : Back
1.23 : Left
1.24 : Right
1.25 : Top
1.26 : Bottom
1.27 : Rear perspective view showing another state of use with a monitor
1.28 : Perspective
1.29 : Rear perspective view
1.30 : Front
1.31 : Back
1.32 : Left
1.33 : Right
1.34 : Top
1.35 : Bottom
1.36 : Rear perspective view showing another state of use with a monitor
1.37 : Perspective
1.38 : Rear perspective view
1.39 : Front
1.40 : Back
1.41 : Left
1.42 : Right
1.43 : Top
1.44 : Bottom
1.45 : Rear perspective view showing another state of use with a monitor

The broken lines indicate portions of the article that form no part of the claimed design; the broken lines in Reproductions **1.9**, **1.18**, **1.27**, **1.36** and **1.45** depicting a monitor represent environmental subject matter that forms no part of the claimed design. Reproductions **1.1** to **1.8** show the claimed design in a first position; Reproductions **1.10** to **1.17** show the state in which the monitor arm is rotated to the left; Reproductions **1.19** to **1.26** show the state in which the monitor arm is fully rotated to the left; Reproductions **1.28** to **1.35** show the state in which the front bracket is rotated backwards; and Reproductions **1.37** to **1.44** show the state in which the front bracket is rotated forward.

to **1.35** show the state in which the front bracket is rotated backwards; and Reproductions **1.37** to **1.44** show the state in which the front bracket is rotated forward.
